UNITED STATES PATENT OFFICE.

EDWARD P. FOLLETT, OF DULUTH, MINNESOTA.

STREET-INDICATING DEVICE.

1,305,271.

Specification of Letters Patent. Patented June 3, 1919.

Application filed August 11, 1917. Serial No. 185,787.

To all whom it may concern:

Be it known that I, EDWARD P. FOLLETT, a citizen of the United States, residing at Duluth, in the county of St. Louis and State 5 of Minnesota, have invented certain new and useful Improvements in Street-Indicating Devices, of which the following is a specification, reference being had therein to the accompanying drawing.

10 This invention consists of certain new and useful improvements in street indicating devices for vehicles and relates particularly to such devices for use in street cars.

15 The principal objects are simplicity of construction and practicability.

Another object is to provide means whereby portions of the device requiring alterations or changes may be quickly and conveniently removed from the remainder of 20 the device for such purpose.

Other objects and advantages of my novel construction will appear in the further description of the invention.

In the illustrated embodiment of the device,

Figure 1 represents a front fragmental elevation partly in section of the device, with the front portion of the housing removed,

Fig. 2 is an end elevation of the internal 30 mechanism of the device showing the housing in section.

Fig. 3 is an enlarged vertical sectional view partly in elevation of the operating means.

35 Fig. 4 is a similar view of a frictional governing device for the drive shaft, and

Fig. 5 is a similar view of a fragmental portion of the roll controlling means.

In the accompanying drawings like reference characters indicate like parts:

1 represents the rear wall of a rectangular shaped receptacle in which the mechanism is housed. This wall is preferably made of cast metal and is formed with a relatively 45 short projecting flange 2 wholly thereabout and to which flange the side and end walls of the metal housing 3 is securely fixed in any desired manner as for example by rivets or screw bolts 4. Upon the lower side wall 50 of this housing is hinged as at 5 the front portion 6 of the housing, said portion 6 having any desired form of opening 7 through which the lettering upon the indicator may be viewed. The opening 7 may or may not 55 be covered by a suitable glass as illustrated at 8. The upper edge of the portion 6 of

the housing may be provided with any desired form of clasp 9 for holding it in place against the coöperating portion of the housing, as is obvious.

60

Fixed to the inner face of the wall or plate 1 or formed integral therewith as preferred are four forwardly projecting struts 10, two adjacent each end of the plate and spaced vertically from each other. The outer extremity of each pair of struts 10 carry a vertically disposed bar 11 which is attached to the struts by means of suitable screws 12. These bars preferably extend both above and below the struts 10 a short distance. Centrally positioned within these bars is journaled the driving shaft 13 of the mechanism. Upon the driving shaft and adjacent each end thereof is securely fixed a sprocket disk 14 having substantially semi-circularly 75 shaped sprockets 15 formed integral upon the peripheral edge thereof, said edge being in the form of a flat surface intermediate of the sprockets as at 16.

70

As a means for imparting intermittent rotating motion to the shaft 13, I have illustrated two ratchet wheels 17, as being fixed to the shaft and spaced apart one upon each side of the center thereof, and it will be noted that each ratchet wheel is provided 85 with the same number of teeth as formed upon the sprocket disk 14 for reasons appearing later.

80

In Fig. 3 I have illustrated the ratchet wheel 17 which is designed for turning the 90 shaft in an anti-clockwise direction, the reciprocal operating pawl 18 being adjacent the under side of the wheel, the reverse of such arrangement being required for operating the shaft 13 in a clock-wise direction, 95 that is to say, the ratchet cogs upon the other wheel 17 are just the reverse of those illustrated in Fig. 3 and the operating pawl will occur above said wheel as is obvious. The pawl 18 is pivotally carried upon a reciprocal pitman 19 the head end 20 of which is larger in diameter than the remainder thereof and which end slidably fits within the supporting cylinder 21, either screw threadedly mounted within the plate 1 of the receptacle or formed integral therewith as preferred. Intermediate of the shoulder formed by the enlargement of the head 20 of the pitman and the inner end 22 of the cylinder and surrounding the pitman is carried 110 an expansive spiral spring 23 which normally holds the pitman fully extended as

100

105

110

illustrated in the sketch. A projection 24 is formed upon the lower front end of the cylinder 21 and is provided with an upwardly turned lip 25 which is designed to impinge 5 the shoulder 26 formed upon the hub portion of the pawl 18 which is pivoted upon the pin 27, thus when the pitman is fully extended as illustrated the pawl 18 will remain in its lowermost position and disengaged 10 from the ratchet wheel 17. A flat leaf spring 28 is fixed as at 29 to the lower face of the cylinder 21 and protrudes beyond the forward extension of same and is arched upwardly to bear against the under side of the 15 pawl 18, whereby, when the pitman 19 is drawn in such a manner as to disengage the shoulder 26 from the lip 25 the pawl will be instantly raised to engagement with the ratchet wheel 17. By this arrangement the 20 pawl is normally held from engagement with the ratchet wheel 17, which permits of the operation of the mechanism by either one or the other of the pawl engaging devices independently. A pin 30 is fixed transverse 25 the head 20 of the pitman 19 and protrudes laterally therefrom. Slots 31 are formed in the two horizontally opposed sides of the cylinder 21 and in which slots the protruding ends of the pin 30 reciprocate to prevent the pitman revolving in the cylinder 21.

Intermediate of the ratchet wheels 17-17 is securely fixed to the shaft 13 a disk 32 having V-shaped notches 33 about the peripheral edge thereof, said notches corresponding in number to the number of sprockets on the disk 14. Directly opposite the peripheral edge of the disk 32 is formed integral with the back 1, a cylindrical hollow projection 34 in which is reciprocally mounted a pitman 35 having an enlarged outer head 36 thereupon and in back of which is mounted a spiral spring 37 for normally holding the pitman in its outermost 40 position, said pitman being held against turning by a transverse protruding pin 37 fixed therein and operative within opposite slots 38 similar to the arrangement disclosed in the pawl carrying pitman 19. The outer 45 extremity of the head 36 of the pitman 35 is bifurcated as at 39 and carries within said bifurcated portion a pin 40 carrying a roller 41 for engaging the peripheral edge of the disk 32 and when encountering one of the 50 notches 33 in said disk, exerts a tendency to hold the disk against revolution and thus acts as a governing device to the rotation of the shaft 13 and tends to hold same in its predetermined position resulting from 55 the pawl and ratchet mechanism above described.

Removably carried upon the bars 11-11 is a rectangular shaped frame comprising the end walls 42-42 and the sides 43-43. 60 This frame is made removable by having

notches 44 and 45 formed in one edge of the end walls thereof, the upper notches 44 being made to hook over suitable pins 46 fixed within the upper end of the bars 11 and the lower notches 45 made to register with suitable pins 47. A dog 48 is pivotally mounted upon each end 42 of said frame adjacent the notches 45 for the purpose of hooking over the pins 47 when the frame is in place and the dogs are maintained in such hooked position by means of any suitable spring 49 or they may be made to maintain such position by gravity. 75

In the upper and lower portions of the frame 42-43 are rotatably mounted two 80 rolls 50 and 51. Each of these rolls is mounted upon an axle 52 non-rotatably fixed within the end walls 42-42 of the supporting frame but readily removable therefrom and which mounting is accomplished by the 85 extreme ends 53 of the axle being made rectangular in cross-section and designed to slip within an elongated slot 54 where it normally assumes an angular position to said slot and engages behind a shoulder 55 there- 90 in in a manner very similar to the common and well known mounting of a curtain roll. Adjacent each end of each shaft 52 is formed a reduced portion as at 56 and upon which the ends of the rolls are rotatably mounted 95 as is also at one end a spring equalizing disk 57. As a means for maintaining rotative tension upon the rolls, two spiral springs 58 and 59 are employed about each axle, the latter being spirally wound about the 100 axle 52, one end 60 of which is made secure to the shaft and the opposite end 61 made secure within the disk 57; and the former being wound about the latter and having one end 62 fixed to the disk 57 and the opposite 105 end 63 fixed in one end of the roll. I have found in practice that the springs operate to best advantage by the inner-one being made of somewhat smaller wire than the outer one, and the object of the idle disk 57 is to 110 maintain proper co-action of the springs, the inclination of the spiral of the springs being in opposite directions to avoid their becoming abnormally frictionally engaged. By this arrangement of spring tension for 115 the rolls it is found that the maximum number of turns of the roll may be accomplished with uniform and satisfactory tension. About the rolls 50 and 51 is mounted the street indicating film or sheet 64, it being of any desired material and having the street designations thereupon and spaced to properly register with the opening 7 in the front of the receptacle. Adjacent the side edges of the film 64 are formed a plurality 120 of holes 65 spaced apart the proper distance to register with the sprockets 15 upon the wheels 14 and by the action of which sprockets the film is operated in either direction. The springs within the rolls 50 125

130

and 51 are so mounted as to properly coöperate with and resist the action of the film for the purpose of keeping a uniform tension thereupon.

5 In Fig. 2 of the drawings I have illustrated the two ratchet wheels 17 as being operated by an electric magnet in the form of a solenoid 66, which may be intermittently controlled by any desired form of 10 electric switch not shown, and which may be located for convenient manual operation either by the conductor or motorman of the car to which the mechanism is applied. While I have illustrated this form of manipulation of the pitman, 19, it is to be understood that a suitable rope or cord may be attached to the eye 67 formed in the pitman 19 and illustrated in Fig. 3 of the drawings and by which the pitman may 15 be reciprocated manually if so desired.

As a means for holding the rollers in any predetermined state of rotative tension in respect to the springs, as for example when placing a new indicating film thereabout, I 20 provide a thumb-screw 68 opposite one end of each roller and screw-threadedly mounted within one end 42 of the roller supporting frame. By this means the free roller may be turned against the tension of its 25 inclosed springs any number of revolutions desired and there securely held by causing its coöperating screw 68 to forcibly impinge the end thereof.

From the foregoing it is evident that I 30 have devised a simple form of indicator, the film rolls of which may be removed or adjusted with the least amount of labor and annoyance, and that it involves but a single operation to substitute one film for another. 35 upon the rolls when such becomes necessary.

Having thus described my invention, what I do claim and desire to secure by Letters Patent is:

1. A street indicator for vehicles comprising 40 a suitable housing, a support fixed to one vertical wall of the housing inside of and adjacent each end thereof, a shaft rotatably carried upon the supports, a rigid rectangular shaped frame removably carried upon the supports independently of 45 the shaft, rollers carried within the frame,

a film coöperatively wound around the rollers, means carried by the shaft for operating the film and means for intermittently operating the shaft.

2. The combination with a street indicator of the character described having a pair of spaced rollers carrying an operative film, of a pair of spiral springs within each roller, one within the other and longitudinally thereof for imparting a rotary stress in opposite directions in each roller.

3. The combination with a street indicator of the character described comprising a pair of vertically spaced rollers, an indicating film coöperatively wound about the rollers, a shaft intermediate of the rollers, means upon the shaft and engageable with the film for operating the latter and means for operating the shaft, of a pair of spiral springs within each roller for imparting a rotary stress in opposite directions to each roller.

4. The combination with a film carrying roller of the character described of a pair 75 of spiral springs disposed longitudinally within the roller, one within the other and wound in opposite directions and means whereby the stress of the springs are made to coöperate in their action upon the roller.

5. The combination with a street-indicator of the character described comprising a pair of vertically spaced rollers having an indicating film coöperatively wound thereabout, a shaft intermediate of the 85 rollers, means upon the shaft and engageable with the film for operating the latter and means for operating the shaft, of a disk fixed to the shaft and having a plurality of notches in the peripheral edge thereof 90 and a spring controlled roller engageable with the notches for holding the disk yieldably by such engagement substantially as described.

In testimony whereof I hereunto affix my signature in the presence of two witnesses:

EDWARD P. FOLLETT.
